UNITED STATES PATENT OFFICE.

CHARLES W. CURRIER, OF COLUMBUS, OHIO.

GAS-BURNER.

SPECIFICATION forming part of Letters Patent No. 701,303, dated June 3, 1902.

Application filed September 20, 1901. Serial No. 75,843. (No model.)

To all whom it may concern:

Be it known that I, CHARLES W. CURRIER, a citizen of the United States, residing at Columbus, in the county of Franklin and State 55 of Ohio, have invented a certain new and useful Improvement in Gas-Burners, of which the following is a specification.

My invention relates to the improvement of gas-burners of that class in which a plurality of burner-supporting arms are made to radiate from a central supply-head or valve-casing; and the objects of my invention are to provide an improved valve construction and pilot-light whereby a comparatively small 60 flame may be maintained in position for lighting the various burners, to so construct and arrange my improved valve mechanism and pilot-light as to insure an increased flame at the mouth of the pilot-burner tube when the 65 main valve is operated to supply the gas to the burner-supporting arms, and to reduce the pilot-light after the flame has been communicated to the burners. These objects I accomplish in the manner illustrated in the accompanying drawings, in which—

Figure 1 is a vertical section of my improved gas-supply head on line $x-x$ of Fig. 2. Fig. 2 is a sectional view on line $y-y$ of Fig. 1.

Similar numerals refer to similar parts 30 throughout both views.

In carrying out my invention I employ a gas-supply head or main valve-casing 1 having an upper end socket 2, into which leads the lower end of a vertical gas-supply pipe 3. 35 From the lower end of the socket 2 leads downward a central port 4, which communicates with a central valve-chamber 5. From this valve-chamber lead radially outward pipe-arms 6, from which are adapted to extend upward burner-supporting arms 7, which may be surmounted by mantles 8 or other suitable burners. Leading vertically through the lower portion of the valve-casing or head 1 is the threaded stem portion of a needle-valve 9, 40 the latter having a suitable enlargement 10 on its lower end to facilitate the turning of the same. As indicated in the drawings, the upper and preferably conical end of the valve 9 is adapted to close communication between the 45 port 4 and the chamber 5. The upper portion of the valve-body 9 is provided with a central

vertical port or recess 11, the upper end of which is adapted to be made to communicate with the lower termination of the port 4, as shown. Leading into the lower portion of the 55 internal port 11 from the threaded outer side of the valve 9 is a short transverse port 12. Leading into an internally-threaded socket 13, formed in the lower portion and inner side of the head 1, is a short horizontal pipe-arm 14, 60 which at its outer end terminates in a vertical valve-casing head 14^a, the upper side of this casing-head receiving the lower end of a vertical pilot-light tube 15, the communication between which and the interior of the 65 valve-casing 14^a is regulated by a needle-valve 16. Leading from the end of the pipe-arm 14 through the casing 1 to the periphery of the valve 9 is a horizontal port 17, the latter being adapted to register with the port or 70 opening 12.

Although in the drawings I have for the sake of clearness in illustration shown but one of the burner-supporting arms 7 and one of the burners 8, it is obvious that one of these 75 burner-arms and burners being supported from each of the pipe-arms 6 will result in the pilot-burner tube 15 being projected between two of said burners.

In the construction of my device the ports 80 12 and 17 are so located with reference to each other that when the valve 9 is in its innermost or closed position said ports will be out of direct communication, the only communication between the same being through 85 the comparatively narrow grooves 12^a, formed by the threads on the periphery of the valve. In case there is not, as ordinarily exists, sufficient play between the engaging threads the threads at this point may be slightly filed 90 to provide a passage for the gas. The gas which enters the head 1 from the pipe 3 and passes through the ports 4, 11, and 12 and thence through the threaded grooves to the port 17, arm 14, and pilot-burner tube 15 is 95 sufficient to maintain a comparatively small flame at the upper end of said pilot-tube and between the burners. When the valve 9 is turned, however, to the position indicated in the drawings—that is, so as to inclose the 100 port 4 and establish communication between the latter and the chamber 5 and admit the

gas to the burners 8—the ports 12 and 17 are in the first part of the operation of thus turning on the gas to the burners made to register one with the other. During the registering 5 of these two ports it is obvious that a greater flow of gas is attained through the ports 11 and 17 to the pilot-burner tube 15, with the result that an increased flame is provided at the outer end of the latter, which will serve 10 to ignite the gas at the adjacent burners, the flame from these burners being communicated to the remaining burners. The operation of turning on the gas being continued, it is obvious that the ports 12 and 17 are again 15 thrown out of direct communication, and the flow of gas through said ports is sufficiently retarded to decrease the flame at the pilot-tube mouth.

From this construction and operation it 20 will be readily understood that improved means are provided for maintaining a pilot or igniting flame in desirable proximity to the burners and that this flame is increased when ignition is desired. It will also be seen 25 that this operation of regulating the flame or volume of gas at the outlets of both the burners 8 and the pilot is controlled by one valve.

Having now fully described my invention,

what I claim, and desire to secure by Letters Patent, is—

In a gas-burner, the combination with a valve-casing; a gas-supply pipe leading downward therein, said casing having formed therein an internal chamber and an inverted valve-seat in the top of said chamber, and a port 30 leading thereto; a vertically-arranged valve loosely mounted in the casing and controlling the vertical port said valve having a port in line with the port of the casing and adapted to be in communication therewith; said casing being provided with a port at right angles to the valve's port; and burner-supporting arms radiating from the casing and in communication with said chamber; of a pipe 35 extending from the casing in communication with its right-angled port; and a tube at right angles to the said pipe having a valve-seat in its end, and a vertically-adjustable valve in the end of the pipe adapted to contact the seat in the tube and control the flow 40 of gas through the tube.

CHARLES W. CURRIER.

In presence of—
C. C. SHEPHERD,
EDWARD M. TAYLOR.
